COMPACTING MACHINE FOR HEAVY LEATHER

Richard W. Daniels, Jr., and John J. Maciejowski,
Wenham, Mass., assignors to United Shoe Machinery Corporation, Flemington, N. J., a corporation of New Jersey

Application November 20, 1951, Serial No. 257,336

4 Claims. (Cl. 69—1)

1

This invention relates to machines for compressing or compacting leather and improving the finish thereof.

More particularly it relates to an improvement in machines of the general type disclosed in United States Letters Patent No. 2,571,149, granted on October 16, 1951, on an application filed in the names of John J. Maciejowski and Richard W. Daniels, Jr.

In this type of machine heavy forces are involved in properly compacting leather and therefore the work element supporting structure is necessarily of massive proportions. The work elements form the passage through which a work piece is carried and must be in proper alignment. Likewise the clearances in this passage are critical in their adjustment and must be maintained with accuracy.

When leather is to be compacted by this machine it usually contains 30% to 50% moisture and in some types of operation the surface of the leather has been coated with water or other aqueous compounds immediately prior to the compacting operation. In the operation of the machine this condition of the leather causes foreign matter to form on and adjacent to the work elements and after continued operation of the machine such a formation or deposit will impede the proper operation of the machines or will cause a marking of the work elements. It is, therefore, necessary that the work elements be frequently cleaned and inspected. To accomplish this end it is also desirable that the work treating zone be completely accessible.

It is an object of this invention to provide a leather compacting machine, of the type wherein work pieces are compacted in a work treating zone by reciprocating flat horizontal bars against yieldable anvils, with ready access to the work treating zone.

In accordance with the features of this invention the anvils are mounted in a pivotal member and counter-balancing means are provided so that the member may be readily moved to and from its operative position.

These and other features of the invention will now be described in detail in the specification and pointed out more particularly in the appended claims.

In the drawings,

Fig. 1 is a view in elevation of the right side or end of a machine in which the present invention is embodied, the head or anvil supporting member of the machine being shown as moved or pivoted into its inoperative position and the feed

2

rolls of the machine placed in their ineffective or open positions;

Fig. 2 is a view in elevation of the left side or end of the machine shown in Fig. 1 with portions being cut away for ease of illustration and the anvil supporting member or head of the machine being in its operative position and with the feed rolls closed;

Fig. 3 is a rear view of the machine with portions omitted or broken away showing internal details of the construction;

Fig. 4 is a sectional view drawn to a larger scale showing in greater detail the construction as brought out in Fig. 2;

Fig. 5 is a sectional view along the line V—V of Fig. 1 drawn to a larger scale and illustrating a locking means for the head of the machine;

Fig. 6 is a sectional view drawn to an enlarged scale along the line VI—VI of Fig. 4; and

Fig. 7 is an electrical diagram showing suitable circuits for the control of the work feeding rollers of the machine.

Because of the nature of the work performed the machine as herein illustrated and in which the invention is embodied is rugged and substantially built. A base is provided which conveniently comprises a horizontal plate 10 (Figs. 1 and 2) and channel bars 12 and 14 the flanges of which rest upon the plate 10. The machine proper comprises two end castings 16 and 18 which are adapted to rest upon the channels 12 and 14. The end castings 16 and 18 are joined by a horizontal box-like casing 20 (Figs. 2, 3 and 4) which is heavily constructed and the ends of which are bolted to the end castings 16 and 18. One side of the casing 20 (toward the rear of the machine and to the left as shown in Fig. 4) is provided with an opening over which is bolted a cover 22. Above and spaced from the casing 20 is a horizontal head casting 24 (Figs. 2 and 4) which includes a top horizontal portion 26 (Figs. 2 and 3) and a lower horizontal portion 28 (Fig. 4). The head casting 24 is adapted to be supported on the end castings 16 and 18 but is conveniently arranged to be moved relative thereto as will be further described.

The front of the machine (to the left in Fig. 1) is provided with a shelf 30 supported on brackets 32 joined to the end castings 16 and 18. A similar shelf 34 is provided on the rear of the machine and is supported by means of brackets 36 joined to the end castings 16 and 18.

The end casting 16 is provided with an opening 40 (Figs. 1 and 3) in its lower portion and an upstanding projection 42 on its top. The pro-

jection 42 is suitably ribbed at 43 to insure adequate strength. The end casting 16 also is provided with horizontal and integral webs 44 and 46 (Fig. 1) as well as a horizontal flat shoulder 48 (Fig. 3).

The end casting 18 is provided with horizontal webs 52 and 54 (Fig. 2) and three flat horizontal surfaces 56, 57 (Fig. 2) and 58 (Fig. 4). The two shoulders 48 and 58 of the end castings 16 and 18 respectively are adapted to cooperate as will be further explained. The relative positions of these two shoulders is illustrated in Fig. 3.

The casing 20 is of cast construction with five webs or partitions 60 therein as depicted in Fig. 3. Each web 60 is provided with a roller bearing 62 and end bearings 64 and 66 are mounted in the end walls of the casing 20. The seven bearings 62, 64, and 66 rotatively support a shaft 70 which runs full length of the casing 20 and protrudes through the end casting 16 to support a flywheel 72 keyed thereto with its hub or pulley 74. Belts 76 are mounted upon the pulley 74 and are driven from a pulley 78 joined to the shaft of a motor 80. The motor 80 is suitably mounted on a pivoted platform 82 (Fig. 1) which is so mounted that it may be moved up or down to vary the tension in the belts 76. Alternating with the bearings 62 on the shaft 70 are six roller bearings 84 and each of these are eccentrically mounted on the shaft 70 to support an eccentric member 85 which has an arm 86 (Fig. 4) pivoted at 88 to a depending and bifurcated portion 89 of a rocking member 90. A shaft 92 is non-rotatably supported in the webs 60 and each of the rocking members 90 is mounted on the shaft 92 to rotate or oscillate thereon. Each rocking member 90 has oppositely extending arms 94 and 96 to which are pivoted short links 98 and 100, respectively. There are two links 98 and two links 100 for each rocking member 90. The upper ends of the links 98 and 100 are pivoted to the lower ends of vertically extending plungers 102 and 104 respectively which are adapted to reciprocate vertically in the upper or horizontal wall of the casing 20. There are two plungers 102 and two plungers 104 to each of the six eccentric members 85. There are, therefore, twelve plungers 102 and twelve plungers 104. These plungers are directly opposite each other with respect to the shaft 92 and are not in staggered relation although such arrangement is permissible. Openings 103, 105 and 107 are formed in the webs 60 to permit assembly of the parts described above and also to permit an adequate circulation and distribution of a lubricant within the casing 20.

The upper portion of the casing 20 is provided with a groove 108 (Fig. 4) into which the tops of twelve plungers 102 extend. The casing 20 is also provided with a groove 110 into which the tops of the plungers 104 extend. Each plunger 102 is pivoted by a pin 112 to a depending rib 114 of a horizontal bar 116 which runs the full length of the row of plungers 102. The plungers 104 are similarly pivoted to a bar 118. It will be understood that the bar 116 and the twelve plungers 102 are adapted to move as a unit and that the same is true of the bar 118 and the twelve plungers 104. The top surfaces of the bars 116 and 118 are smoothly contoured as seen in Fig. 4.

Recessed into and attached to the top of the casing 20 are three bars 120, 122 and 124 to which are attached work guiding plates 126, 128 and 130, respectively.

The bottom portion 28 of the head casting 24 is fitted with angle bars 132 and 134 (Fig. 4) to

which are attached guide plates 136 and 138. Beneath and along the center of the head casting 24 are flanges 140 and 142 and to the flange 140 a central work deflecting and air restricting plate 144 is attached. The plate 144 cooperates with the plates 136 and 138 to provide under surfaces which define with the aid of the upper surfaces of the plates 126, 128 and 130 a shallow work passage. These guide plates (six in number) are mounted contiguous to the work treatment zone and to the path through which the work is to be fed and the plates 128 and 144 are interposed between and immediately above the two rows of plungers 102 and 104.

A row of anvils 150 (nineteen in number) are mounted for vertical motion through the bottom portion 28 of the head casting 24 and are placed in cooperative relation with the row of plungers 102. A second row of anvils 152 are provided in the head casting 24 and are placed to cooperate with the row of plungers 104. The anvils 150 are similar in all respects to the anvils 152 and only the anvils 152 are therefore specifically described.

Fig. 6 clearly depicts the construction of each anvil 152 (similar to each anvil 150) which is bored at 154 to accommodate a spring loaded plunger 156. A coil spring 158 is provided within the plunger 156 and is retained in place by a spring washer 160 retained in a groove 162 formed in the main body of the anvil 152. The anvil 152 is also provided with a shoulder portion 164 which is adapted to rest upon a top surface of the lower portion 28 of the head casting 24 with a shock absorbing or resilient material 166 interposed. A coiled spring 168 is arranged normally to maintain each of the anvils 152 in firm engagement with the shock absorbing material 166 and the upper end of each of the springs 168 is held downwardly with the proper compression by means of a headed screw member 170 (Fig. 2) which is threaded into the upper portion 29 of the head casting 24. The bottom of the spring-loaded plunger 156 is provided with a web 172 (Figs. 6 and 4) which is arranged to project into a slot 174 of a tiltable work contacting anvil member 176 as well as into a groove 178 (Fig. 6) of a pin 180 which is utilized to pivotally attach the anvil member 176 to the main body of the anvil 152. It will be noted that the work contacting anvil portion 176 is curved in the direction of the pin 180 but is provided with flat and vertical ends which (Fig. 3) are placed in substantially abutting relation with the adjacent anvil portions 176. The arrangement of each anvil portion 176 with respect to the main body of its anvil 150 or 152 is such that a slight pivoting motion of the portion 176 about the pin 180 is permitted.

The end casting 18 is provided with an upstanding portion 182 (Figs. 2 and 3). This portion cooperates with the upstanding portion 42 of the end casting 16 to aid in holding the head casting 24 and two rubber covered feed rolls 184 and 186 (Fig. 4) in position. Bolted and dovetailed to the upstanding portions 42 and 182 are four bearing blocks 188 (Fig. 3), 190 (Fig. 3), 192 (Fig. 1) and 194 (Fig. 2). These bearing blocks are not split but are so made as to be slipped over the ends of their respective shafts (to be referred to) during the assembly of the machine. The bearing blocks 188 and 190 serve to support a shaft 196 of the rubber covered roll 184. The bearing blocks 192, 194 support a shaft 198 which is part of the roll 186. Located on shoulders of

the end casting 18 are two bearing blocks 200 and 202 (Figs. 1 and 2) which serve to support stub shafts 204 and 206 respectively. The stub shaft 204 bears a gear 208 mounted to rotate thereon and the stub shaft 206 carries a gear 210 for rotation relative thereto. The gear 210 is in mesh with a gear 212 keyed to the shaft 196 and also with a gear 214 mounted on a stub shaft 216 supported on the end casting 18. The gear 214 is mounted to drive a gear 218 which is keyed to the shaft 220 of a lower steel feed roll 222. The latter roll with its shaft 220 is mounted to rotate on bearings in the inner ends of two pivoted arms 223 and 224. The stub shaft 216 is of sufficient length to support the arm 224 for pivotal action as well as the gear 214 and the arm 223 is pivoted to the end casting 16 by means of a bolt 225. The end of the arm 224 (Figs. 2 and 3) is provided with a depending lug 226 which is pivoted by means of a pin 227 to the upper end of a rod 228 and the lower end of the rod 228 (Fig. 2) passes freely through the top of a casting 230 and is threaded and supplied with a stop nut 232. The casting 230 is pivoted by means of a pin 234 (Fig. 2) to one end of a two-armed lever 236 and the latter is pivoted at 238 to a special fitting 240 supported on the horizontal web 52. The other end of the two-armed lever 236 is pivoted at 242 to the lower end of a piston rod 244 which is part of a hydraulic motor 246. The latter is pivoted by means of a pin 248 to a depending portion 250 of the end casting 18. At the other side of the machine, the pivoted arm 223 bears a depending lug 252 to which is pivoted at 253 (Fig. 4) a depending rod 254, the lower end of which is threaded and passes through a casting 256 and bears a stop nut 258 (Fig. 1). The casting 256 is pivoted at 260 to one end of a two-armed lever 262. The lever 262 is pivoted at 264 to a special fitting 266 supported on the horizontal web 46 of the end casting 16. One end of the lever 262 is pinned at 268 to the lower end of a piston rod 270 which is part of a fluid pressure motor 272 and the latter is pivoted at 274 to a depending portion or web 276 of the end casting 16.

A stop member 280 is made an integral part of the web 46 and placed to conform to one end of the two-armed lever 262, as shown in Fig. 1. A stop member 282 (Fig. 1) is also made a part of the end casting 16 and is in position to limit the movement in one direction of the special casting 256. Similar stops 284 and 286 are provided on the end casting 18, as seen in Fig. 2.

A second steel feed roll 290 is provided and is mounted beneath and parallel with the rubber covered roll 186. The mounting of this roll 290 is not specifically described as it is clearly shown in the drawings and the mounting is similar in all respects with that of the roll 222 except that the swinging of the roll in coming into effective feeding relation is opposite to that of the roll 222 (clockwise instead of counterclockwise as viewed in Fig. 4).

A valve 292 (Fig. 1) is placed on the back of the machine and on the end casting 16 and this valve is connected in a well-known manner to control the operation of the two fluid motors 246 and 272. A second valve 294 is mounted on the front of the machine on the end casting 16 and similarly controls the two motors 296 and 298 utilized for opening and closing the roll 290.

The head casting 24 is adapted to be rotated with respect to the rubber covered roll 186 and therefore away from and toward its normal and

operative position by virtue of its mounting in the bearings 300 and 302 (Fig. 3). One-half of each of these bearings constitutes a portion of the head casting 24 and each bearing is split with the outer half being joined to the casting 24 by means of bolts. The bearing 300 utilizes bolts 304 and 306 and the bearing 302 employs bolts 308 and 310. The bearing 300 is interposed between the bearing block 188 and one end of the main portion of the rubber roll 184, and the bearing 302 is interposed between the other end of the main portion of the roll 184 and the bearing block 190. Supported on one end of the head casting 24 is a bifurcated arm 312 to the end of which is pivoted a depending rod 314 which is part of a counterbalancing unit (Fig. 1) made up of a concentric coiled spring 316, expansive force of which (when the head casting 24 is at or less than 45° from its normal or operating position) is utilized in a conventional manner to pull downwardly on the arm 312. A bracket 313 is attached to the end casting 16 by a stud and nut 315. The rod 314 is free to slide and pivot in passing through the bracket 313. The arm 312 is held to the head casting 24 by means of a cap plate 320 bolted to the head casting 24 by means of bolts 322. A similar counter-balancing unit utilizing an arm 324 is employed at the other end of the head casting 24. This unit has a depending rod 326 and a coiled spring 328 and is held in slideable and pivotal relation with the end casting 18 by a nut 329. It will thus be seen that the head casting 24 is held in rotative relation with the shaft 196 and special means must be provided for normally holding the head casting 24 in accurate and operative relation with respect to the lower parts of the machine. This accuracy obviously is necessary because of the small dimensions dealt with in the treatment of leather and will be more clearly understood as the description proceeds. The end castings 16 and 18 have already been referred to as having horizontal shoulders 48 and 58. These serve together with the bearings 300 and 302 to support the head casting 24 and interposed between the shoulders 48 and 58 and the appropriate parts of the head casting 24 are wedges or shims 330 and 332 (Fig. 3). These wedges or shims may be varied in thickness or number positively to determine the exact clearance desired for particular work to be treated.

In order to hold the head casting 24 firmly down on the wedges or shims 330 and 332, wedges 334 and 336 are provided near the top of the machine. As clearly depicted in Fig. 3, the upstanding projection 42 of the end frame 16 is recessed or grooved at 340 to accommodate the wedge 334, and the head casting 24 is correspondingly recessed (for that same wedge) at 342. The upper and lower surfaces of these recesses 340 and 342 are not in the same planes as clearly shown in Fig. 3 and the construction is such that movement of the wedge 334 into place serves to wedge that end of the head casting 24 downwardly against the wedge or shim 330. After the wedge 334 is firmly driven into place or drawn into place by a suitable bolt 350, bolts 352 may be tightened firmly locking the wedge 334 and that end of the head casting 24 in position. The wedge 336 for the other end of the head casting is similarly provided with an adjusting bolt 354 and tightening bolts 356.

The head casting 24 is provided with five vertical passages 360 (Fig. 3) serving as air ducts leading from the vicinity of the work guiding

plate 144 to an air suction hood 362 bolted at 364 to the top of the head casting 24. The means disclosed for removing dirt and other extraneous matter from the work treating zone is not claimed herein but is the subject of an application for United States Letters Patent Serial No. 350,951, filed April 24, 1953 in the names of Richard W. Daniels, Jr., and John J. Maciejowski. The hood obviously must be disconnected in the event that the head casting is to be tilted.

The lower steel roll 290 is adapted to be driven by a gear 364 which in turn is driven by a gear 366 and the gear 208.

A motor RM (Fig. 7—and not shown in Figs. 1 to 6, inclusive) is utilized to drive a shaft 310 (Figs. 2 and 3) to which is keyed a sprocket 312 for driving a chain 374. This chain drives a sprocket 376 (Fig. 2) which is keyed to the shaft 196. The shaft 198 is driven from the shaft 196 by means of sprockets 380, 382 (Fig. 1) and a sprocket chain 384. It will be noted that the sprocket 382 is slightly larger in diameter than the sprocket 380. This is for the reason that the rubber covered feed roll 184 (at the zone of work discharge) must be driven at a slightly faster rate than the feed roll 186 as each work piece is elongated during the treatment, as will be further brought out.

The upstanding projection 42 of the end frame 16 (Fig. 5) is bored at 390 to accommodate a spring pressed plunger 392 to which a knob 394 is pinned, the knob having a finger 396 for engaging a shoulder 398 on the projection 42. The head casting 24 is drilled at 400 to receive the plunger 392 when the head casting 24 is in a temporary lowered position. A second plunger with a knob 401 is similar to the plunger 392 and is provided for holding the head casting 24 in its raised position as shown in Fig. 1. Both of these plungers are not essential but are provided merely for convenience. The plunger with the knob 401 has been found to be much more useful than the plunger 392.

A safety bar 404 is located adjacent to the roll 186 and immediately above the path of travel of a workpiece W and is supported in this position by curved arms 406 secured to a shaft 402 which is mounted for rotation on the bearing blocks of the roll 186. Also secured to the shaft 402 is an arm 408 (Fig. 4) which abuts the bearing block for the roll 186 limiting the downward movement of the bar 404. A spring 410 is provided which tends to hold the bar 404 in its normal position. A safety switch SS is mounted on the front of the machine (Figs. 4 and 7) which is adapted to be operated by a projection on the right hand arm 406 when the bar 404 is raised by a workpiece which becomes fouled in the work treating zone.

Fig. 7 diagrammatically depicts the electrical control system for the machine. Three phase current is drawn from the three lines ML and a transformer T is utilized to provide suitable current to operate four magnetic coils A, B, C and D. The coil A is arranged to operate a relay K1 for controlling the motor 80 driving the work compacting tools. The coil B is adapted to close a relay K2 and the coil C is adapted to close a relay K3. The coil D operates a pneumatic time delay relay K4 (within the confines of the dash lines of Fig. 7). The secondary line from the transformer T is controlled by a stop button or switch SB the operation of which terminates all current flow.

The tool motor 80 is started by closing a switch

TS and energizing the coil A which closes the relay K1. The contactor a serves to hold the relay K1 closed after the switch TS is released and opened and the motor 80 therefore continues running.

The motor RM for driving the feed rollers 184, 186, 222 and 290 is started by closing a switch RS to energize the coil B and closing the relay K2. The circuits controlling the feed motor RM are so connected that the feed rollers may be stopped almost instantaneously. This is performed by the opening of the safety switch SS (when leather is caught or buckled under the bar) to deenergize the coils B and D. This causes the contactor m of the relay K4 to close, and because of the action of a dash-pot DP, the contactor n remains closed for a time depending upon how fast air is permitted to flow into the dash-pot cylinder. While the contactors m and n are closed the circuit is completed through the relay K3 to reverse the current to the motor RM. This brings the motor RM, and hence the feed rollers, quickly to a stop. The dash-pot DP air inlet is adjustable so that the contactor n will open just before the motor RM is completely stopped and thereby remove the reverse voltage so that the feed rolls are not driven in directions opposite to those in feeding the work. The safety apparatus is not claimed herein but is the subject of an application for United States Letters Patent Serial No. 350,952, filed April 24, 1953, in the names of Richard W. Daniels, Jr., and John J. Maciejowski.

In the event that a momentary reversal of the feed rolls and motor RM is desired after that motor has been stopped and in order to free jammed work, for example, a button or switch JS is employed. Closing the switch JS serves to energize the coil C and the feed rolls are reversed as long as the switch JS is depressed.

Only the switch SS is shown in the drawings as placed on the machine but the switches SB, TS, RS and JS may all be grouped at the front of the machine or on the shelf 38 within convenient access for the operator.

From the above description it may be understood that the head casting may easily be lifted for cleaning of the work treating tools and that buckling of the work W may be avoided with the controls provided.

Having described our invention, what we claim as new and desire to secure by Letters Patent of the United States is:

1. In a machine for compacting hides, a frame, means on said frame for feeding a spread-out work piece in a path leading through the machine, tools on said frame comprising reciprocable flat bars arranged transverse and contiguous to said path and anvils arranged in cooperative relation with said bars and at the other side of said path, and a supporting member for said anvils, said member being movable away from said path giving access to said bars and anvils.

2. In a machine for compacting hides, a frame, means on said frame for feeding a spread-out work piece in a horizontal path through the machine, tools on said frame comprising reciprocable flat bars arranged transverse beneath and contiguous to said path and anvils arranged above said path in cooperative relation with said bars, and a supporting member for said anvils, said member being in pivoted relation with said frame for upward movement away from said path giving access to said bars and anvils.

3. In a machine for compacting hides, a frame, cooperating rollers on said frame for feeding and discharging a spread-out work piece with relation to a work treating zone in said machine, tools on said frame comprising reciprocable flat bars arranged transverse and contiguous to said zone and anvils arranged in cooperative relation with said bars and at the other side of said zone, and a movable supporting member for said anvils, said member being normally locked in operative position on said frame and being provided with counterbalancing means to facilitate movement of said member to gain access to said bars and anvils.

4. In a machine for compacting hides, a frame, 15 cooperating feed rollers on said frame for feeding a spread-out work piece in a horizontal path

leading through a work treatment zone of the machine, tools on said frame for compacting work passing through said zone, and a supporting member for that portion of the machine located above said zone, said member being normally locked in operative position but being pivoted and counterbalanced for movement away from operative position to gain access to said tools.

RICHARD W. DANIELS, JR.
JOHN J. MACIEJOWSKI.
